(54) **SPINNING THREAD, OF WOOL**

(76) Inventor: **William Bell**

William Bell
Sethers Patent.

The Schedule referred to in this Sethers Patent and making part of the same contains a description in the words of the said William Bell himself, of his improvement being a machine for making threads of wood for making Mats, Hindoo-blinds, Table covers, &c.

My improvement consists in making a frame of any suitable length and breadth, similar to a Carpenter's common plane in form. At the front end of this frame is block part of this machine is a block for the insertion of a square or oblong block of wood or metal for the purpose of holding in a circular, resembling what is commonly called a "beam" or horse-tail. They are held fast by screws, screwed into the side of the block touching three sides. The square or oblong block of wood or metal which contains them is let into the face of the block part of this machine, and according to one of its dimensions. At a suitable distance from the block which holds the wood or metal there is a piece of metal, angular or square fastened, driven into the block, by counter-bursh-screws, to secure it in its place. Half of the inside edge of the upper plate is bevelled off to correspond with a sliding knife or splitter, similar to a common plane iron, for the purpose of splitting the wood in a direction contrary to which the teeth split it, so as to form the wood into shreds. The third plate lies on the upper part of the second piece of metal which has an inclined plane for the purpose of raising or depressing the knife, as well as for cutting coarse or fine, and has a screw let into it which passes through the third plate in an oblong mate, likewise for regulating the size of the shreds. A fourth plate with its under edge corresponding to the cutter is driven on the face of the block, covering half the width of the knife for making it even. The block or frame part of this machine is hollow half of its length for the purpose of admitting and letting out the shreds or threads of wood. On the side of this machine is fast a piece of wood propelling in towards the centre of the block, on the bottom of the same, for a way or direction to this machine when out the piece of wood is projected. It is operated on by hand. The plane ^{which} from the shreds or threads of wood is to be taken can be in an inclined or horizontal direction.
